UNITED STATES PATENT OFFICE.

FRANCIS J. STRAUB, OF NEW KENSINGTON, PENNSYLVANIA.

CONCRETE-BLOCK MACHINE.

Application filed November 16, 1926. Serial No. 148,678.

This invention relates to improvements in block forming machinery for the manufacture of concrete blocks and similar articles. It has for its object to provide means for final tamping and finishing the top of the block, in connection with a machine of standard well known construction.

As is generally understood, building blocks when molded in an ordinary stripper block machine, are usually tamped by a series of 10 gravitating power elevated tamps located above the mold and operable therein and around the usual cores for the block openings, with final removal of the block by 15 vertical lifting.

Ordinarily, the tops of such blocks are finished after tamping, either by simply striking off the excess material, or by such removal and then smoothing the top of the block by lowering a finishing plate thereon and driving it downwardly to the level of the top of the mold by striking the back of the finishing plate with the tamps.

One of the objects of the present invention is to provide means for supporting the finishing plate so it will be held flexibly and resiliently, subject to the shocks of the blows from the tamps, without strain or injury to the plate or its parts, while at the same time 20 permitting the finishing plate to properly adjust itself as it is driven slightly into the mold cavity, with suitable movement limitation.

Another feature of improvement and advantage is in providing means in connection with an adjustable feeding hopper for striking or wiping off excess material after the usual tamping, whereby the end portions of the block are left somewhat higher than 30 the middle portion, providing excess material for reinforcement of the ends and corners in the final plate actuated tamping operation.

In the accompanying drawings I have 45 illustrated the invention as utilized in connection with one well known form of molding machine and its supply hopper, in which:

Fig. 1 is a partial sectional view, showing 50 a portion of the mold and its tamps, with the hopper in filling position;

Fig. 2 is an end view thereof, showing one form of tamping plate in elevated position;

Fig. 3 is a plan view of Fig. 1;

Fig. 4 is a view similar to Fig. 3, showing the finishing plate lowered to operative position;

Fig. 5 is a view in side elevation, similar to Fig. 1, showing the finishing plate lowered 60 within the mold, as in Fig. 4;

Fig. 6 is a sectional detail view, showing the mounting of the finishing plate;

Fig. 7 is a detail cross section on the line 65 VII-VII of Fig. 1;

Fig. 8 is a cross section through the tamping and pressing plates, showing a modified construction;

Fig. 9 is an upper face view of the pressing plate, showing a further modified arrangement, omitting the upper plate;

Fig. 10 is an end view thereof.

In the drawings, 2 represents the upper portion of the molding machine, within which the blocks are molded around the 75 usual cores, and provided with the customary lifting plate and other accompanying features, not shown.

For the purpose of supplying the raw aggregate, a hopper 3 is movably mounted 80 by means of structural members 4 at each side, as channels, whereby the hopper is adapted to travel back and forth on supporting rollers 5 of brackets 6.

The latter are secured to and extend upwardly at each outer side from longitudinal cross plate members 7, which extend slightly laterally from the molding machine, for such mounting. Hopper 3 is provided with a supporting floor 8, and upwardly extending 90 side walls 9 and an end wall 10 terminating slightly below the bottoms of the tamps 11 when elevated, as in Figs. 1 and 5.

As thus made the hopper is capable of being moved upon its rolling trackway into 95 registering position with the mold as in Fig. 1, or backwardly away therefrom for lowering of the finishing plate as in Fig. 5.

The finishing plate is adapted to be automatically folded upwardly into vertical position when not in use, to provide clearance for the tamps 11 when the hopper is moved away from the mold, and to be lowered into registering position therewith, for final top surface finishing, as shown in Fig. 5.

For such purpose a rock shaft 12 is mounted in brackets 13 secured on the outer front portions of channel members 4, providing a rocking support for the plate. Arms 14 are pivotally mounted by their hubs 110

15 on shaft 12, and are provided with rearwardly extending counterweighted arms 16, adapted to throw the arms 14 and the finishing plate upwardly when not in use, as in Fig. 1.

At the outer ends of arms 14, a terminal elongated cross bar 17 is loosely mounted by means of a pin 18 having a countersunk bearing connection with bar 17 and a re-
tracting cushioning spring 19 at the other side of arm 14. Said spring tends to normally retract the bar 14 by its bearing against washer 20, secured by cotter pin 21 or otherwise, as clearly shown in Fig. 6.

15 The finishing plate 22 is of a length and width to fit neatly within the upper edges of mold 2. It is securely mounted by countersunk rivets underneath elongated bar 17, and a similar shorter bar 23, which 20 together form the supporting framework for the finishing plate.

An upper tamping plate 24 is also fixedly connected with bars 17 and 23 between arms 14 and adapted to receive the impact of the tamps 11, while bars 17 and 23 extend across the ends of the mold, limiting its downward movement within its upper edges.

The ends of outer elongated bar 17 are utilized as handles when lowering the finishing plate into working position, and the finishing plate 22 itself is provided with clearance openings 25 for the cores.

As thus constructed it will be seen that when the finishing plate and tamping plate are thrown over into registering positions with the mold, the upper face of the block may be compressed and finished by the tamps 11, down to exactly the desired extent, and with an even and condensed surface formation.

For the purpose of scraping off any surplus material from the top of the mold, after the usual preliminary filling and

Figs. 9 and 10 show a modified construction of mounting of the finishing plate by countersunk flat faced rivets 28 on the main supporting cross bars 17 and 23.

Bar 17 is flexibly and resiliently mounted by spring cushioned studs 18 underneath the swinging arms 14 as above described. In such construction the tamps 11 strike across the middle space above the finishing plate, against bars 17 and 23 at the same time, with an evenly distributed action on the finishing plate against the aggregate. The

The construction and operation of the machine, and its advantages in use will be readily understood and appreciated by all those familiar with this class of mechanism.

A finished block having been removed from the machine in the usual way, the customary pallet is first placed on the bottom plate of the mold, and the hopper is moved over into registering position, for delivery of aggregate into the mold cavity. During the usual tamping by tamps 11, these joint operations will be continued until the mold is filled and tamped to the top. 90

Thereafter any surplus is removed, leaving the end portions of the contents somewhat higher than the middle, and with the hopper moved out of register, the finishing plate and tamping plate are lowered to position, as in Fig. 5. Thereupon, plate 22 or 22^a makes contact with the uneven upper portion of the aggregate, and the tamps 11 are again started.

In falling they strike the tamping plate 100 continuously over its entire surface, or against bars 17 and 23, Figs. 9 and 10, imparting a lowering and packing action to finishing plate 22. Bars 17 and 23 eventually come into arresting contact with the upper edges of the mold, when the operation is completed. 105

mounted finishing mechanism adapted to be lowered into the molding machine for finishing of the contents thereof.

2. The combination with a molding machine and tamps therefor, of an adjustably mounted finishing mechanism consisting of a supporting frame provided with a flexibly connected finishing plate and limiting abutments providing for arrested movement of the plate within the molding machine.

3. The combination with a molding machine and tamps therefor, of an adjustably mounted finishing mechanism consisting of a pivotally mounted counterweighted supporting frame, and a finishing plate flexibly and resiliently mounted on the frame for lowering insertion within the molding machine.

4. The combination with a molding machine and tamps therefor, of an adjustably mounted finishing mechanism consisting of a pivotally mounted counterweighted supporting frame, and a finishing plate flexibly and resiliently mounted on the frame for lowering insertion within the molding machine, and provided with upper supporting and tamping members.

5. The combination with a molding machine and tamps therefor, of an adjustably mounted tamping mechanism consisting of a pivotally mounted counterweighted supporting frame, and a finishing plate flexibly

and resiliently mounted on the frame for lowering insertion within the molding machine and provided with cross bars adapted to engage the top of the molding machine, 35 and an upper tamping surface.

6. In a block molding machine, the combination with an open top mold, of a feeding hopper, and a counterweighted frame pivoted thereto having a flexibly mounted 40 finishing plate insertible within the mold for tamping.

7. In a block molding machine, the combination with an open top mold, of a feeding hopper, and a counterweighted frame 45 pivoted thereto having a flexibly mounted finishing plate insertible within the mold and provided with upper tamping members for action thereon by vertically acting 50 tamps.

8. In a block molding machine, the combination with an open top mold, of a feeding hopper, and a counterweighted frame pivoted thereto having a flexibly mounted 55 finishing plate insertible within the mold and provided with clearance openings for the cores of the mold and upper tamping members for action thereon by vertically acting tamps.

In testimony whereof I hereunto affix my 60 signature.

FRANCIS J. STRAUB.
